COILING MACHINE

Emmett S. Ellis, Detroit, Mich., assignor to Kelsey-Hayes Wheel Company, Detroit, Mich., a corporation of Delaware

Application July 22, 1936, Serial No. 91,934

16 Claims. (Cl. 153—56)

The invention relates to coiling machines and refers more particularly to machines for coiling a strip of stock of angular cross section to form an arcuate member of substantially the same 5 cross section. While the machine forming the subject matter of the invention is capable of other uses than illustrated, it is of particular utility when employed to form an arcuate brake shoe from a strip of stock of angular cross section.

The invention has for one of its objects to provide a machine having rolls angularly spaced about and cooperable with the master roll, these cooperable rolls being carried by bearings 15 slideable on the frame of the machine so that the machine may provide for stock of different thickness.

The invention has for another object to provide a machine in which the cooperable rolls 20 are independently movable toward and away from the axis of the master roll so that each cooperable roll will do its intended amount of work.

The invention has for still another object to 25 provide a machine in which the cooperable rolls are subjected to pressure by means arranged and constructed to allow the cooperable rolls to tilt and thereby compensate for variation in thickness of the stock as it passes through the machine transversely of its length.

The invention has for a further object to construct the machine so that the amount of pressure exerted upon the cooperable rolls may be readily varied.

The invention has for still further objects to provide the machine with a stripper for removing the formed member from the master roll; to provide means operable in timed relation to the master roll for operating the stripper; to provide 35 a sectional master roll and to release the pressure holding the sections in predetermined relation to each other prior to operation of the stripper; and to construct the frame of the machine so that all of the rolls may be readily removed and replaced.

The invention has for other objects the novel arrangements and combination of parts as more fully hereinafter set forth.

In the drawings:

50 Figure 1 is an end elevation of a coiling machine showing an embodiment of my invention;

Figure 2 is a cross section on the line 2—2 of Figure 1;

55 Figure 3 is a front elevation, partly in section, of a part of the machine;

Figure 4 is a cross section on the line 4—4 of Figure 3 and showing, in addition, the means for driving the cam shaft;

Figure 5 is a cross section on the line 5—5 of Figure 2;

Figure 6 is an enlarged cross section on the line 6—6 of Figure 2; and

Figure 7 is an enlarged cross section on the line 7—7 of Figure 1.

The coiling machine, as illustrated, is adapted 10 to form a straight strip of T-section stock into an arcuate brake shoe having a web and a head, to which latter a brake lining is secured. The brake shoe coiling machine in general comprises a base 1, three upright frame members 4, 5 and 15 6 mounted upon the base, a master shaft 7, a series of shafts 8, and a crown 9 secured to the upper ends of the frame members and tying the same together.

The master shaft 7 is journaled in the anti-friction bearings 4', 5' and 6', which latter are fixedly secured to and carried by the frame members 4, 5 and 6 respectively. The series of shafts 8 comprise the upper shaft 10 and the back shafts 11, 12 and 13. The upper shaft 10 is journaled 20 in three anti-friction bearings 10', 10² and 10³, which bearings are slidably mounted on the frame members 4, 5 and 6 respectively in directions radially of the master shaft 7 and toward and away from its axis, these frame members 30 being provided with suitable guides for this purpose. The back shafts 11, 12 and 13 are also journaled in bearings constructed and arranged in the same manner as the bearings for the upper shaft 10 to individually slide radially of the master shaft and toward or away from its axis. 35

14 is a master roll between the frame members 4 and 5 and secured to the master shaft 7 to rotate therewith. This master roll comprises the sections 15 and 16, the section 15 being keyed 40 to the master shaft and the section 16 being sleeved upon the section 15 and being keyed thereto. These sections are shaped to provide the radial annular space 17 therebetween to receive the web of the T-section stock and to prevent this web from becoming wrinkled while the stock is being coiled to form the arcuate brake shoe. The section 15 is slightly movable axially relative to the section 16 to provide for initial entrance of the web into the space and to also 45 provide for release of the web after the brake shoe has been formed. To secure this slight axial movement, I have provided the hydraulic plunger 18 which encircles the master shaft 7 and abuts the section 15. This plunger is slidable 50 55

within the cylinder 19 which also encircles the master shaft and which, in addition, abuts the collar 7' formed upon the master shaft. 20 is an abutment engageable with the section 16 and held from movement by means of the collar 21 threaded upon the master shaft. All of these parts are located between the frame members 4 and 5.

The upper shaft 10 has the roll 22 secured thereto to rotate therewith, this roll being positioned to cooperate with the master roll 14, the strip of stock passing between these rolls. As shown, the roll 22 is keyed to the shaft 10 and is secured in place between the frame members 4 and 5 by the spacer 23 and the collar 24. The spacer abuts the end wall 25 of the box of the anti-friction bearing 10² and the collar is threaded upon the shaft. The back shafts 11, 12 and 13 also have secured thereto rolls for cooperating with the master roll 14 and these rolls are positioned and held in place in the same manner as the roll 22.

The master shaft 7 is driven by means of the gearing 26 which may be driven by any suitable prime mover, such as an electric motor. The upper shaft 10 and the back shafts 11 and 12 above the back shaft 13 are adapted to be driven from the master shaft 7 by gearing 27 located between the upright frame members 5 and 6. This gearing includes the ratchet gear assembly 28 which is constructed to normally positively drive the upper shaft 10 from the master shaft 7 and to also allow the upper shaft 10 to rotate at a higher rate than the master shaft 7, if for any reason the strip of stock passing between the master roll 14 and the roll 22 frictionally drives this roll at a higher rate. The ratchet gear assembly comprises the gear 29 journaled upon the upper shaft 10, the pocket member 30 keyed to the shaft 10 and the dog 31 pivoted upon the gear 29 and adapted to extend into the pockets 32 upon the member 30 and to have driving engagement with the ends of these pockets.

For the purpose of positioning the rolls upon the shafts 10, 11, 12 and 13 in predetermined relation to the master roll 14, I have provided a hydraulic system which is so constructed that each of these rolls is subjected to the same pressure acting in a direction toward the axis of the master roll. The construction is also such that each of these rolls is movable independently of the others. 33 is a conduit connected at one end to a suitable central pressure system, such as a pump and the associated means for driving and controlling the pump. This conduit is adapted to conduct liquid under pressure to individual cylinders and this liquid acts upon a piston in each of these cylinders, which in turn through associated mechanism exerts pressure upon the roll associated therewith radially of and toward the axis of the master roll. Inasmuch as the arrangement for each of the cooperable rolls is the same, that for the cooperable roll 22 only will be described. In detail, 34 is a pressure bar extending parallel to the axis of the upper shaft 10 and abutting the boxes of the anti-friction bearings 10', 10² and 10³ diametrically opposite the axis of the master shaft 7. This pressure bar is preferably fixedly secured to the boxes of the anti-friction bearings 10² and 10³. 35 is a cylinder in the crown 9 having its axis in alignment with the axes of the upper shaft 10 and master shaft 7 and located outwardly beyond the pressure bar 34. 36 is a piston within this cylinder and having the central hemi-spherical bear-

ing 37 which abuts and fulcrums upon the pad 38 fixedly secured to the pressure bar 34. This pad preferably has the hemi-spherical recessed bearing 39 for fitting the bearing 37. The axes of the cylinder 35, piston 36 and bearings 37 and 39 are 5 preferably located midway between the median planes of the anti-friction bearings 10' and 10² and also between the extended ends of the roll 22. As a result of this construction, it will be seen that the cooperable roll 22 will be held in a predetermined relation to the master roll 14 and also that this roll may angularly tilt to compensate for variation in thickness of the strip of stock passing between this roll and the master roll transversely of the length of the stock. 10 15

Individual check valves 40 are provided in the connections between the conduit 33 and each of the cylinders in the crown 9 to prevent the cooperable rolls upon the shafts 10, 11, 12 and 13 from being affected by movement of one. These check valves permit entry of the liquid under pressure into the cylinders, but prevent discharge from the cylinders. As a result, it will be seen that each of the cylinders is subjected to the same pressure which may be readily varied as desired to enable the machine to take care of stock having heads of different thickness. 20 25

For the purpose of removing the arcuate brake shoe from the master roll after the brake shoe 30 has left the roll upon the lower back shaft 13, I have provided a stripper which is or may be operable in timed relation to the master roll. For the purpose of releasing the pressure exerted by the roll sections 15 and 16 of the master roll 14 after the strip of stock has become coiled into an arcuate brake shoe and left the roll upon the lower back shaft 13, I have provided means which is operable in timed relation to the master roll 14 to release the pressure in the cylinder 19. As shown, 41 is a stripper bar which may have its 40 inner end positioned in operative position adjacent the master roll 14 to engage the leading end of the formed brake shoe. 42 is a valve in the pressure line including the cylinder 19. As shown in the present instance, both the stripper bar and valve are adapted to be operated after the master roll has made two complete revolutions. In detail, 43 is a shaft mounted upon the frame of the machine, the shaft being journaled, as shown, upon the auxiliary frame member 44 which is secured 50 at the front of the machine to the upright frame members 4 and 5. This shaft is driven by means of the sprocket wheel 45 secured thereto, the sprocket wheel 46 upon the master shaft 7, and the sprocket chain 47, the former sprocket wheel having twice the number of teeth of the latter sprocket wheel. 48 is a cam fixed upon the shaft 43 and respectively controlling the stripper bar 41 to urge the same into operative position adjacent the periphery of the master roll and to also allow the stripper bar to move upon its guide 49 longitudinally outwardly and away from the master roll into inoperative position under influence of the spring 50. 51 is a second cam fixed on the shaft 43 and operable in substantially the same manner as the cam 48 to operate the valve 42. 55 60 65

In the event that the formed brake shoe is to be removed upon one revolution of the master roll, the stripper bar may be fixedly secured in operative position. 70

To guide the straight or substantially straight strip of stock into the machine and between the master roll and the upper roll, I have provided the guide members 52 and the spring pressed roll 75

53 which are carried by the auxiliary frame member 44. The auxiliary frame member also carries the stripper bar 41 and the valve 42.

For the purpose of permitting the master roll 5 and the cooperable rolls to be readily removed and replaced, the upright frame member 4 is movably mounted upon the base 1. As shown 54 is a screw journaled in the base 1 and extending longitudinally thereof and 55 is a nut secured to 10 the lower end of the upright frame member 4. Upon removing the studs which secure the crown 9 to the upper end of this upright frame member and the studs which secure the auxiliary frame member 44 to this upright frame member 15 and also the sprocket wheels and chain, the screw can be rotated to move the frame member 4 and the anti-friction bearings carried thereby away from the frame member 5 and longitudinally of the master shaft 7 to a position clearing this 20 master shaft and also the shafts 10, 11, 12 and 13 a sufficient distance to enable removal of the positioning collars and the rolls and subsequent replacement.

What I claim as my invention is:

25 1. In a coiling machine, the combination with a master roll, of rolls angularly spaced with respect to said master roll and adapted to cooperate therewith, said last mentioned rolls being radially movable toward and away from the axis 30 of said master roll, and means independent of the stock being coiled for exerting pressure upon said last mentioned rolls independently of each other in directions toward the axis of said master roll.

35 2. In a coiling machine, the combination with a frame, of a shaft journaled upon said frame, a master roll upon said shaft, rolls angularly spaced with respect to said master roll and adapted to cooperate therewith, shafts for said last mentioned rolls, bearings for said last mentioned shafts slidably mounted on said frame to move radially of said master roll, means adapted to be controlled from a single source for normally maintaining said bearings in predetermined relation to said shaft for said master roll, and means for driving said shaft for said master roll and certain of the shafts for said other rolls.

40 3. In a coiling machine, the combination with a master roll and a roll adapted to cooperate therewith, of means for applying pressure to said second mentioned roll radially of and toward the axis of said master roll, said means comprising cooperating elements with one fulcruming on the other within the extended ends of said 45 second mentioned roll.

45 4. In a coiling machine, the combination with a master roll and a roll adapted to cooperate therewith, of means for applying pressure to said second mentioned roll toward the axis of said 50 master roll, said means being arranged and constructed to provide for tilting of said second mentioned roll upon variation in thickness of the stock passing between said rolls transversely of its length.

55 5. In a coiling machine, the combination with a frame, of a shaft fixedly journaled upon said frame, a master roll upon said shaft, a second shaft, a roll upon said second shaft adapted to cooperate with said master roll, bearings for said second shaft slidably mounted upon said frame toward and away from the axis of said master roll, a pressure bar engageable with said last mentioned bearings, and means for exerting pressure upon said pressure bar in a direction 60 toward the axis of said first mentioned shaft,

said pressure applying means being fulcrumed upon said pressure bar within the confines of the extended ends of said first mentioned roll, and means beyond the ends of said rolls for driving said shafts.

6. In a coiling machine, the combination with a master roll, of rolls angularly spaced with respect to said master roll and adapted to cooperate therewith, said last mentioned rolls being independently movable toward and away from the axis of said master roll, and hydraulic means for exerting pressure upon said last mentioned rolls independently of each other in directions toward the axis of said master roll.

7. In a coiling machine, the combination with a master roll, of rolls angularly spaced with respect to said master roll and adapted to cooperate therewith to form an arcuate section from a strip of stock, and a stripper radially movable into and out of engageable position with the formed arcuate section to disengage the same from said roll.

8. In a coiling machine, the combination with a master roll, of rolls angularly spaced with respect to said master roll and adapted to cooperate therewith to form an arcuate section from a strip of stock, a stripper engageable with the formed arcuate section to disengage the same from said master roll, and means for actuating said stripper in timed relation to said master roll.

9. In a coiling machine, the combination with a master roll formed of sections movable relative to each other in axial directions, of means for applying pressure to one of said sections to normally hold the same in a predetermined relation to the other of said sections, rolls angularly spaced with respect to said master roll and adapted to cooperate therewith to form an arcuate section from a strip of stock passing between said rolls, and means for automatically releasing the pressure, said means being operable in timed relation to said master roll.

10. In a coiling machine, the combination with a master roll, rolls angularly spaced with respect to said master roll and adapted to cooperate therewith and shafts for said first and second mentioned rolls, of a frame comprising frame members at opposite ends of said first and second mentioned rolls, and bearings on said frame members for said shafts, one of said frame members being movable relative to the other to disengage the bearings carried by said movable frame member from said shafts whereby said rolls are made accessible.

11. In a coiling machine, the combination with a master roll, rolls angularly spaced with respect to said master roll and adapted to cooperate therewith and shafts for said first and second mentioned rolls, of a base, frame members upon said base at opposite ends of said first and second mentioned rolls, bearings carried by said frame members for each of said shafts at the opposite ends of the rolls thereon, and cooperating means upon said base and one of said frame members for moving said last mentioned frame member in a direction parallel to the axes of said shafts.

12. In a coiling machine, the combination with a master roll, of rolls angularly spaced with respect to said master roll and adapted to cooperate therewith, said last mentioned rolls being movable toward and away from said master roll, and means independent of the stock being coiled for exerting pressure upon said last mentioned rolls toward said master roll.

13. In a coiling machine, the combination with a frame, of a shaft fixedly journaled upon said frame, a master roll upon said shaft, a second shaft, a roll upon said second shaft adapted to cooperate with said master roll, bearings for said second shaft slidably mounted upon said frame toward and away from the axis of said master roll, a pressure bar engageable with said last mentioned bearings, and means independent of the stock being coiled for exerting pressure upon said pressure bar in a direction toward the axis of said first mentioned shaft.

14. In a coiling machine, the combination with a master roll and a roll adapted to cooperate therewith to form a rolled section of stock, of a stripper normally radially spaced from the periphery of said master roll, and means for moving said stripper toward the periphery of the master roll to disengage the rolled section from the master roll.

15. In a coiling machine, the combination with

a master roll, of rolls angularly spaced with respect to said master roll and adapted to cooperate therewith to form an arcuate section from a strip of stock, a stripper, means for moving said stripper into operative position adjacent the periphery of the master roll, and means for rotating the master roll to move one end of the rolled arcuate section into engagement with said stripper to disengage the arcuate section from the master roll.

16. In a coiling machine, the combination with a master roll, of rolls angularly spaced with respect to said master roll and adapted to cooperate therewith, said last mentioned rolls being independently movable toward and away from the axis of said master roll, and means for exerting pressure upon said last mentioned rolls independently of each other in directions toward the axis of said master roll.

EMMETT S. ELLIS. 20
